Robert M. Barr.

ATTORNEY

UNITED STATES PATENT OFFICE.

HAROLD LICHTEN, OF PHILADELPHIA, PENNSYLVANIA.

STOCKING TOP.

Application filed February 26, 1924. Serial No. 695,208.

The present invention relates to an improvement in the welt or top of hosiery.

Some of the objects of the present invention are to provide a welt having strengthening characteristics to offset the wear and strain of a garter or supporter of the grip type; to provide a stocking welt having a continuous reinforcing band knit in and around it; to provide a stocking welt with a reinforcing band for cooperation with a garter or a supporter and providing means for indicating the location of the reinforced portion; to provide an improved reinforced stocking welt; and to provide other improvements as will hereinafter appear.

In the accompanying drawings, Fig. 1 represents a stocking top or welt embodying the present invention in the first stages of the knitting process; Fig. 2 represents the same in the second stage; and Fig. 3 represents the welt or top with the completed stocking knitted thereto.

Referring to the drawings, one form of the present invention is shown and described in conjunction with the making of a full fashioned piece of hosiery, and therefore in considering Fig. 1 it will be understood that the fabric there shown is a single flat piece, knit of a width substantially twice the width of a finished stocking top. In Fig. 1, the knitting of the fabric starts at the knitted course 10, and as initially set up the needles receive a single thread so that the portion so knitted is the ordinary single fabric of the usual stocking construction. This single thread knitting is continued for a suitable distance to give the desired single fabric band for a purpose which will later appear, and then an additional thread is introduced to the needles, for example at the band 11, so that as the knitting machine continues to knit the fabric a band of double thickness fabric 12 will be produced, and the width of this band is preferably such as to accommodate the ordinary round garter or provide sufficient space for the attachment of the grips of the supporter type of garter. In the present instance, this double knit fabric continues to the course 13, where the extra thread is thrown out, and the knitting machine resumes the single thread knitting, and knits a band 14, the length of which is approximately twice the length it is to be in the finished stocking. When this length of single knitted fabric has been completed, a line of colored thread, or thread having

characteristics different from the thread theretofore used, is introduced, as shown at 15, and as soon as this is knitted into the fabric, the additional thread is again thrown into the needles and continued until the width of this double knit band 16 is the same as the first double knitted band 12 between the courses 11 and 13. When the width of this last band has been completed, another thread of different color is introduced, as shown at 17, so that the double knit fabric is definitely located by the indicating means forming respectively the bands 12 and 16. With the completion of this last identifying course, the knitting machine goes back to the knitting of the single fabric, and finishes a length corresponding to the length between the reference numerals 10 and 11, the last length being indicated by 18. The top or welt formed by the steps just described in connection with Fig. 1 is now folded transversely on the line 19-19 and the free end placed upon the needles of the machine to form a seam 20, Fig. 2, extending across the fabric, and from then on the machine knits the stocking leg of the ordinary single ply fabric. When the proper length of the stocking has been knit, it is removed from the machine and transferred to a footer, which knits or attaches the foot to the leg of the stocking, while a seaming machine completes the stocking by forming a seam 21, Fig. 3, lengthwise of the back of the stocking after the latter has been folded lengthwise on the line 22, Fig. 2. The completed stocking embodying the present invention is shown in Fig. 3, and consists of an inner and an outer top band 23 of single fabric, an inner and an outer reinforced part of double thickness 24, which serves to receive the garter, and an inner and an outer single knit band 25, from which the stocking leg of single fabric continues. The transverse bands 15 and 17 by reason of the folding over of the band 12 are displayed on the outer circumference of the welt, and definitely indicate and define the width of the reinforcement or fabric of double thickness upon which the garter is located or to which a supporter grip can be attached.

From the foregoing, it will be apparent that by the present invention a stocking welt is formed of double thickness of material extending circumferentially about the top of the stocking proper. Within the confines of this welt there is a continuous band of

double knit fabric both on and knit into the inner and outer portions of the welt, so that the welt, in addition to having a double thickness, is also provided with a reinforcement in which the fabric contains more threads than are in the single fabric. This welt is particularly adapted to withstand the wear of either a round garter or a garter with grips, and to the latter it is particularly suited because the grips may be placed at any part of the reinforced band because all portions thereof are of equal strength and durability.

While but one form is shown in which this invention may be embodied, it is to be understood that the invention is not limited to any specific construction or to a specific use to full fashioned hosiery, as obviously it might be employed with seamless stockings or

stockings made on a circular machine and applied in various forms without departing from the spirit of the invention or the scope of the appended claim. 20

Having thus described my invention, I 25
claim:

In a stocking construction, a welt, a continuous reinforcing band extending circumferentially in said welt and formed of fabric knitted with more threads than the body of said welt and of a greater thickness than 30 said body, and a pair of spaced bands on opposite sides of said reinforcing band and formed by knitting a yarn of different color from the yarn in said reinforcing band.

Signed at Philadelphia, in the county of 35
Philadelphia, and State of Pennsylvania,
this 30th day of January, 1924.

HAROLD LICHTEN.
